WEDGE ADJUSTING MECHANISM FOR
LOCOMOTIVE DRIVE BOXES

William A. O'Toole, McKeesport, Pa.

Application March 1, 1935, Serial No. 8,856

9 Claims. (Cl. 105—81)

This invention relates broadly to a wedge adjusting device for use in bearings and has to do particularly with a locomotive drive box or like assembly.

For purposes of explanation and illustration the invention will be described as embodied in a more or less conventional type locomotive drive box assembly, but it will be understood that it may be used in connection with any other bearing assembly wherein adjusting wedges are employed. The invention is in the nature of an improvement over the inventions described and claimed in my United States Letters Patent Nos. 1,580,526 and 1,654,597.

As is well known, each end of each driving axle of a locomotive is received within a bearing device commonly known as a drive box. The drive boxes are retained in the pedestal of the locomotive frame. Each drive box is usually connected with the pedestal by means of a saddle engaging the top of the drive box and also engaging the mid-point of a suitable leaf spring. The ends of the leaf spring are connected with the locomotive frame. Thus when the locomotive is in motion there will be a slight vertical movement between the drive box and the pedestal by reason of wave in track and of the yieldable connection interposed by the spring.

While the drive box must be free to move up and down in the pedestal, it is important that there be substantially no play in the direction lengthwise of the locomotive between the drive box and the pedestal. To prevent such play a wedge is interposed between one side of the drive box and the corresponding side of the pedestal, this wedge being adjusted vertically as wear develops between the drive box and the wedge and between the wedge and the pedestal, such wear developing through the relative vertical motion between the drive box and pedestal.

It is well known to employ spring devices of various kinds for resiliently urging the wedges of locomotive drive box assemblies into position to take up the wear just mentioned. The use of such spring devices has numerous drawbacks and disadvantages, among which is that such a device does not afford a positive positioning of the wedge but only acts on the wedge resiliently. As the wedge advances under the action of the spring the spring becomes less and less effective, and ultimately, unless a hand adjustment is made, the spring will lose its effect entirely. Furthermore, the springs are subjected to the most severe kind of use and springs of the high-

est grade and most expensive spring steel must be used. Even such springs not infrequently fail in use. Moreover, the most successful devices employing springs require the location of such springs at the bottom of the pedestal brace, the same depending several inches below the brace. These spring devices are invariably damaged when the locomotive is derailed, and the use of such springs in switching engines and locomotives of the smaller types is practically prohibited as there is not sufficient clearance below the frames of such locomotives to allow of the positioning therebelow of the necessary spring mechanism.

I provide a wedge adjusting mechanism for a locomotive drive box or like assembly enabling the abolishment of all wedge supporting springs and the disadvantages attendant thereto pointed out above, and having the further advantage that the wedge or other positioning means is positively but automatically moved to and maintained in desired adjusted positions. This makes for a sturdier more rigid construction in which play of the wedges against the springs and the uncertainty of spring action are entirely done away with. My construction is adapted for application to any locomotive pedestal brace and projects therebelow only to a very slight extent.

I utilize the relative movement between the drive box and the frame or pedestal to operate the adjusting means. This may be done in various ways, although I prefer to employ means operated by the relative movement between the drive box and the pedestal to advance the wedge or other positioning means. This may, for example, be accomplished by a cam device in connection with the pedestal brace operating a screw or nut which moves a connecting or thrust member against the wedge.

Other details, objects and advantages of the invention will become apparent as the following description of a present preferred embodiment thereof proceeds.

In the accompanying drawings, I have shown a present preferred embodiment of the invention, in which

Figure 1 is a vertical cross-sectional view of a locomotive drive box assembly;

Figure 2 is a perspective view of a portion of a bracket adapted for connection to the locomotive pedestal brace;

Figure 3 is a perspective view of an operating member adapted for use in connection with the bracket shown in Figure 2;

Figure 4 is a side view of the operating member shown in Figure 3;

Figure 5 is a bottom plan view of the operating member shown in Figures 3 and 4;

5 Figure 6 is a top plan view showing the bracket of Figure 2 and the operating member of Figures 3, 4 and 5 assembled, together with other co-operating parts;

10 Figure 7 is a detail vertical cross-sectional view, taken on the line VII—VII of Figure 6, through a portion of the assembly when in one operative position;

15 Figure 8 is a view similar to Figure 7 through said portion of the assembly when in another operative position; and

15 Figure 9 is a face view of the wedge for taking up the wear between the drive box and the pedestal.

Referring now more particularly to the drawings, there is designated by reference numeral 2 the portion of a locomotive frame commonly known as the pedestal which comprises legs 3 and 4. The lower ends of the pedestal legs are connected together in usual manner by the pedestal brace 5. Received between the legs 3 and 4 is a drive box 6 which carries a journal bearing 7 mounted on the journal of a driving axle 8. Bearings 9 and 10 are interposed between the drive box 6 and the legs 3 and 4, respectively, the bearing 9 being of wedge shape in cross section at its central portion as shown in Figure 1 and having side flanges 11 which embrace the pedestal leg 3.

35 The drive box is closed at the bottom by a closure member 12 which contains suitable means for applying lubricant to the journal. Such means, as shown in Figure 1, comprises a mass of grease 13 urged upwardly toward the journal by a spring 14 bearing against a plate 15 which carries the grease, a perforated protective member 16 bearing directly against the journal and allowing of the application of lubricant thereto.

45 The function of the wedge 9 is, as well known in the art, to position the drive box relative to the pedestal in the horizontal direction or, stated in another way, to take up the wear occurring between the wedge, the drive box and the pedestal during relative generally vertical movement between the drive box and the pedestal when the locomotive is in motion. The wedge is adapted to be moved upwardly as wear occurs, thus taking up the wear and maintaining the drive box in proper guided position at all times.

55 In the preferred embodiment of the invention shown in the drawings a bracket 17 having a central portion as clearly shown in Figure 2 is bolted to the bottom of the pedestal brace 5, as shown in Figure 1. At its bottom the bracket has a relatively small bore 18 and at its top a relatively large bore 19, the latter being open laterally at both sides as shown in Figure 2. Each lateral opening has a substantially flat bottom portion 20 forming a continuation of the seat 21 formed at the offset between the bore 18 and the bore 19, a substantially vertical wall 22 and an inclined wall 23 which slants upwardly and inwardly of the opening. Each of the walls 23 is adapted to function as a cam, as will presently appear. A curved slot 24 is made in the upper surface of the bracket 17 longitudinally at one side of and intersecting the bore 19, as shown in Figure 2, for a purpose to be presently described.

70 There is provided a bolt 25 having a head 26 rounded in one direction and flattened in the other direction, which head is adapted to be received

76 within a slot 27 in the bottom of the wedge 9. The bolt passes downwardly through a bore 28 in the pedestal brace 5 and through the bores 19 and 18 in the bracket 17. Applied to the bolt 25 is a nut 29 of the shape shown in Figures 7 and 8 and which has an upper internally threaded portion 30 threadedly cooperating with the bolt 25, a downwardly projecting sleeve portion 31 and an outwardly projecting annular flange 32. The bottom of the flange 32 is flat and smooth 10 and is adapted to rest upon the seat 21 of the bracket. The upper surface of the flange 32, however, is knurled as shown at 33. In lieu of being knurled, the two contacting surfaces may be "ground", that is, one abraded against the other to provide cooperating faces. This overcomes the wear which occurs where knurling is used.

Surrounding the internally threaded portion 30 of the nut 29 is an operating member 34, shown 20 in Figures 3, 4 and 5, which has generally the shape of a hollow cylinder but with outward projections 35 extending from its cylindrical surface at opposite sides thereof. The cylindrical surface of the operating member 34 also has a notch 36 intermediate the projections 35, as shown in Figure 3. The bottom surface 37 of the operating member 34 is knurled or ground, as shown in Figure 5. Such surface is adapted to rest upon the knurled or ground-in upper surface 33 of the flange 32 of the nut 29 when the parts are assembled, and the projections 35 are adapted to extend outwardly within the oppositely disposed openings in the bracket 17. Each of the projections 35 has a substantially vertical side wall 38 and an inclined side wall 39, the respective walls 38 and 39 being substantially parallel to the respective walls 22 and 23 of the bracket 17. The width of each of the projections 35 is slightly less than the width of the opening in the bracket 17 in which it is disposed, as shown in Figure 6, so that a slight rotative movement of the operating member 34 relative to the bracket is permitted. Disposed in the slots 24 and 36 above described is a spring member 40 tending normally to rotate 45 the operating member 34 in the counterclockwise direction, or opposite the arrows 41, shown in Figure 6.

The operation of the device will now be explained. When the locomotive is in motion the 50 drive box and pedestal are continually moving relatively to each other in the generally vertical direction, as above explained, resulting in increasing wear. Such relative movement results in a generally vertical reciprocatory movement of 55 the wedge 9 relatively to the pedestal and, consequently, relatively to the pedestal brace 5 and the bracket 17. Such movement of the wedge 9 imparts a like movement to the bolt 25.

Now let it be assumed that the parts are in 60 the position shown in Figures 6 and 7 in which the bottom of the nut 29 rests on the seat 21 and the inclined walls 39 of the operating member 34 are urged against and in contact with the inclined walls or cams 23 of the bracket. Upon 65 upward movement of the wedge 9 the bolt 25 is carried therewith and the bolt carries the nut 29, which, in turn, carries the operating member 34. These parts move upwardly to the position shown in Figure 8. During such upward movement the bolt 25 does not rotate by reason of the connection between its head and the wedge 9. However, the engagement between the respective cams 23 and the inclined walls or cam followers 39 of the projections 35 of the operating member 70 75

34 results in a slight rotation of the operating member in the clockwise direction, or in the direction indicated by the arrows 41 in Figure 6. At such time the lower surface of the operating member 34 and the upper surface of the flange 32 of the nut 29 are in contact and tend to be pressed together due to the upward movement of the assembly just described. Under these circumstances relatively great friction exists between the two knurled or ground surfaces with the result that rotation of the operating member causes a corresponding rotation of the nut 29, resulting in a slight upward projection of the bolt 25 and a positive advancement of the wedge into 15 desired adjusted position relative to the pedestal.

Upon downward movement of the assembly just described, as, for example, from the position shown in Figure 8 to that shown in Figure 7, the inertia of the operating member 34 results 20 in a materially decreased frictional resistance between the surface 31 thereof and the surface 33 of the flange 32 of the nut 29. The nut tends to drop from beneath the operating member, this 25 momentarily releasing the operating member, which is returned by the spring 40 to its original position with the respective inclined walls or cam followers 39 thereof in contact with the respective walls or cams 23 of the bracket 17. The parts then assume the position of Figure 7 30 except for the slight rotation which has been imparted to the nut 29 and the corresponding slight upward movement imparted to the bolt 25 by the cycle of operations just explained and the cycle is repeated.

35 The operation above described results in movement of the wedge to desired adjusted positions and positive maintenance of the same therein. It is contemplated that in normal operation no manual adjustment at all will be necessary but 40 easy manual adjustment is provided for in case of necessity by forming the outer surface of the sleeve portion 31 of the nut 29 for reception of a wrench so that a wrench may be applied thereto and the nut turned manually. The interengagement between the inclined surfaces 39 and 45 23, together with the interengagement of the cooperating knurled surfaces 33 and 31 positively prevents the nut from turning so as to permit loosening of the bolt.

50 The amount of movement of the bolt on each cycle of operations as above explained depends on three factors, these being the pitch of the screw, the inclination of the cam surfaces 23 and the amount of rotational movement of the 55 operating member which is provided for. Any or all of these factors may be adjusted as desired and they may be correlated so as to produce the desired movement.

While I have shown and described a present 60 preferred embodiment of the invention, it is to be distinctly understood that the same is not limited thereto but may be otherwise variously embodied within the scope of the following claims.

I claim:

65 1. The combination with a locomotive drive box assembly having a pedestal, a drive box and an adjusting wedge, of an adjusting screw for the wedge, an adjusting nut on said screw, a member for turning the nut in one direction only, cooperating surfaces on said member and a portion of the pedestal for imparting movement thereto in one direction upon relative vertical movement between said member and the frame, and spring means for returning said member to 70 its original position.

2. The combination with a locomotive drive box assembly having a pedestal, a drive box and an adjusting wedge, of an adjusting screw for the wedge, an adjusting nut on said screw, said nut and screw being vertically movable with the wedge relative to the pedestal, an actuating member carried on the nut for vertical movement therewith, cooperating cam surfaces on said member and the pedestal for causing rotative movement of said member in one direction upon relative upward movement thereof, and a spring for returning said member to its original position, said member serving to rotate the nut only when the two are moving upward relative to the pedestal. 15

3. The combination with a locomotive drive box assembly having a pedestal, a drive box and an adjusting wedge, of an adjusting screw attached to the wedge in such manner that both the screw and the wedge move up and down together relatively to the drive box, a nut for limiting the upward movement of the wedge and the screw, and means operable by relative vertical movement between the wedge and pedestal for turning said nut to raise the wedge relatively to the pedestal. 20

4. The combination with a locomotive drive box assembly having a pedestal, a drive box and an adjusting wedge, of an adjusting screw attached to the wedge in such manner that both the screw and the wedge move up and down together relatively to the drive box, a nut for limiting the upward movement of the wedge and the screw, and means for turning said nut to raise the wedge relatively to the pedestal as wear 35 develops in the assembly, said means being operable to turn the nut upon relative motion of the wedge and pedestal in one vertical direction and being ineffective to turn the nut upon relative motion of the wedge and pedestal in 40 the other vertical direction.

5. The combination with a locomotive drive box assembly having a pedestal, a drive box and an adjusting wedge, of an adjusting screw attached to the wedge in such manner that both the screw and the wedge move up and down together relatively to the drive box, a nut for limiting the upward movement of the wedge and the screw, and means for turning said nut to raise the wedge relatively to the pedestal as wear 50 develops in the assembly, said means being operable to turn the nut with an upward relative motion of the wedge in the pedestal and being ineffective to turn the nut upon downward relative motion of the wedge with respect to the 55 pedestal.

6. The combination with a locomotive drive box assembly comprising a pedestal, a drive box in the pedestal and an adjusting wedge between the drive box at one side of the pedestal, of an 60 adjusting screw attached to the wedge in such manner that both the wedge and the screw move up and down together relatively to the drive box, a nut for limiting the relative upward movement of the wedge with respect to the drive box, and means for turning said nut to raise the wedge relatively to the pedestal as wear develops, said means including an actuating member cooperating with the nut and having a cam-engaging surface thereon, a part of the pedestal being provided with a fixed cam surface for cooperation with the cam-engaging surface of said actuating member, said actuating member and said cam surfaces being so arranged that upward movement of the wedge relatively to the pedestal serves 75

to turn said actuating member to turn the nut, said actuating member being provided with means for returning it to its initial position after it has been turned by the action of said cam-engaging surfaces, the relation between the actuating member and the nut being such that the return movement of the actuating member does not turn the nut.

7. The combination with a locomotive drive box assembly having a pedestal, a drive box and an adjusting wedge, of means for adjustably limiting the motion of the wedge upwardly with respect to the pedestal, and means actuated through relative motion between the pedestal and wedge for adjusting the wedge upwardly.

8. The combination with a locomotive drive box assembly having a pedestal, a drive box and an adjusting wedge, of adjustable means for limit-

ing the movement of the wedge upwardly relatively to the drive pedestal and for feeding the wedge upwardly as wear develops between the drive box and pedestal, and means actuated through relative vertical movement between the wedge and pedestal for operating said adjustable means.

9. A locomotive drive box assembly comprising a pedestal, a drive box, an adjusting wedge, a screw member attached to the wedge having a nut element thereon cooperating with a portion of the pedestal for limiting the upward movement of the wedge relatively to the pedestal, and means cooperating with a portion of the pedestal frame and with said nut for turning said nut in one direction only upon relative vertical movement between the wedge and pedestal.

WILLIAM A. O'TOOLE.
